UNITED STATES PATENT OFFICE

WILLIAM H. MUSSEY, OF RICHMOND HILL, NEW YORK

COMBINED HAND-RAIL AND TRAP-DOOR FASTENING

1,052,366.

Specification of Letters Patent. Patented Feb. 4, 1913.

Application filed May 17, 1912. Serial No. 698,058

To all whom it may concern:

Be it known that I, WILLIAM H. MUSSEY, a citizen of the United States, residing at Richmond Hill, Long Island, in the county 5 of Queens and State of New York, have invented certain new and useful Improvements in Combined Hand-Rails and Trap-Door Fastenings, of which the following is a specification.

10 My invention relates to a combined grab-iron or hand-rail and trap-door fastening for passenger coaches.

One of the objects of the invention is to provide a grab-iron combined with a trap-door fastening, the relative position of the latter being such that it lies substantially concealed and protected from accidental disengagement.

A further object of the invention is to 20 combine a grab-iron and trap-door fastening in order to minimize the number of projections in the vestibule of a passenger coach, without impairing the functions of either of the devices.

25 To the accomplishment of the recited objects and others coördinate therewith, the preferred embodiment of my invention resides in that construction and arrangement of parts hereinafter described, illustrated in 30 the accompanying drawings, and embraced within the scope of the appended claims.

In said drawings: Figure 1 is a side elevation of the inside of a vestibule illustrating the general arrangement of the combined grab-iron and trap-door fastening, the front of the vestibule being entirely removed to more clearly show the invention. Fig. 2 is a vertical sectional elevation of the fastening shown in operative position with respect to the upper edge of the trap-door. Fig. 3 is a plan view of the knob containing the fastening device, and Fig. 4 is a side elevation thereof. Fig. 5 is a side elevation of a slightly modified form of fastening used 40 in conjunction with a corner grab-iron, and Fig. 6 is a plan view thereof. Fig. 7 is a top plan view showing the application of the corner grab-iron and trap-door to the inside of the vestibule of a passenger coach, and 45 Fig. 8 is a side elevation thereof.

50 Referring more particularly to the drawings for a detail description of my invention the numeral 1 designates a pair of doors arranged centrally of the vestibule of an ordinary passenger coach, upon either side

and at the bottom of which are arranged trap-doors, as 2 and 3 connected at their lower edges, by hinges 4 to the floor of the car. Each trap-door is provided with a diagonally disposed grab-iron 5, and above 60 the trap-door 2 is located a substantially right angular shaped grab-iron 6, the vertical portion thereof lying adjacent one of the central doors 1 and being suitably sustained by the supports 7, while the horizontal extremity is disposed in parallelism with the upper edge of the trap-door 2 and terminates in a knob, as 8. Above the companion trap-door 3 is the usual switchbox door 9, upon the base of which is secured a 70 short length of grab-iron 10, preferably by the support 11 and the knob 12. If desired, a grab-iron, as 13, may be fastened upon the opposite side of the central doors 1 to correspond with the vertically arranged portion 6 of the first mentioned grab-iron. 75

The knobs 8 and 12 are identical in construction and arrangement, and a description of one will suffice for both. Upon referring to Figs. 2 and 3 it will be noted that 80 the shank 14 of the knob is provided at the top with an elongated slot 15 and at the bottom diametrically opposite the first mentioned slot, with a shorter slot, as 16, both of the slots being disposed longitudinally of 85 the shank proper. These slots are designed to receive a spring latch 17, the same being pivotally secured at its outer end by the transversely extending pin 18. The inner portion of the latch 17 terminates in an upwardly formed or projecting ring 19 to facilitate manipulation of the device, and an angular projection 20 is formed integral with the opposite extremity of the latch, the same normally lying in the path of movement of the upper edge of the trap-door 3. Just below the knob 12 and upon the face of the outer extremity of the latch 17 are arranged a pair of recesses 21 and 22 for the reception of a coil spring 23 for normally 90 maintaining the said latch in active position. Adjacent the base of the shank 14 is a depending flange 24 designed to sustain a buffer, as 25, formed of rubber or any equivalent material which will serve as a 95 cushion. 100

In operation when the door 3 is swung upwardly it engages the outer edge or projection 20 of the latch 17, forcing the latter outwardly against the tension of the spring 110

22 until it rides completely over said projection, whereupon the retractile force of the spring will cause the latch to resume its normal position with the projection 20 in front 5 and in the path of movement of the upper edge of the trap-door. In order to minimize sudden shocks or jars the buffer 25 is provided so that the same will be thoroughly absorbed. Obviously, when it is desired to 10 swing the door in operative position the finger is simply inserted through the ring 19 and the latch 17 pulled upwardly disengage the projection 20 from the edge of the trap-door.

15 In Figs. 5, 6, 7 and 8 a slightly modified form of my invention is illustrated, the same comprising the combination of trap-door fastening means with a vertically arranged corner grab-iron, as 26. In this case the fastening 20 consists of a horizontally arranged projection 27 having a curved base 28, the said projection being bifurcated at its outer end to receive the lower extremity of the latch 29, a pin, as 30, being extended transversely through the members constituting the bifurcation to pivotally secure the latch. A spring 31 is seated in recesses 32 and 33, respectively, of the lower extremity of the latch and the projection 27, while the upper 25 extremity is formed to present a hook 33 and the lower end designed to engage the upwardly curved keeper 34 carried by the trap-door 35, which latter is of a slightly different type from that hereinbefore described.

30 The operation of the fastening device just described is practically the same as that of the other devices. When the door is swung upwardly the outer end of the keeper 34 35 impinges against the lower extremity of the latch 29, and rides over the same and assumes the position illustrated in Fig. 5 of the drawings. Upon constraining the upper hook-like portion 33 of the latch outwardly the lower extremity will be disengaged from the

keeper, and the door may then be readily adjusted in active position.

It should be understood that in its broader aspect the invention comprehends the employment not only of the various means described, but of equivalent means for performing the recited functions. While the arrangement shown is thought at the present time to be preferable, it is desired to reserve the right to effect such modifications and variations thereof as may come fairly within the scope of the appended claims.

What is claimed, is:—

1. The combination with a grab-iron rail having a supporting knob, of a trap-door, 60 said knob having a latch for locking said trap-door.

2. The combination with a grab-iron rail having a supporting knob, of a trap-door, and a latch projecting through opposite 65 sides of said knob and adapted to engage said door.

3. The combination with a trap-door of a support, a spring pressed latch carried by said support and projecting above the top 70 and below the bottom of the latter, the upper portion constituting a handle and the lower portion presenting a catch for said trap-door.

4. The combination with a grab-iron rail 75 having a supporting knob, of a trap-door, said knob carrying a shank, a latch mounted in said shank and adapted to engage said trap-door.

5. A grab-iron rail having a support, and 80 a latch carried by and projecting upon opposite sides of the support to present an operating handle and a trap-door engaging extremity.

In testimony whereof I hereunto affix my 85 signature in presence of two witnesses.

WILLIAM H. MUSSEY.
